[57] CLAIM

The ornamental design for a base for a garden umbrella, as shown and described.

DESCRIPTION

FIG. 1 is a front elevational view of a base for a garden umbrella showing my new design, the rear elevational view being identical thereto;

FIG. 2 is a left side elevational view thereof;

FIG. 3 is a top plan view thereof;

FIG. 4 is a bottom plan view thereof;

FIG. 5 is a partial vertical sectional view thereof, taken along line 5—5 of FIG. 4; and

FIG. 6 is a right side perspective view thereof, to an enlarged scale.

FIG. 1

FIG. 2

FIG.5

FIG. 3

FIG. 4

FIG. 6
